DESK CALENDAR OR SIMILAR ARTICLE

Floyd A. Junkins, Tiffin, Ohio

Application May 14, 1954, Serial No. 30,494

Term of patent 14 years

(Cl. D74—5)

FIG. 1.

FIG. 2.

FIG. 3.

FIG. 4.

To all whom it may concern:

Be it known that I, Floyd A. Junkins, a citizen of the United States and a resident of Tiffin, county of Seneca, and State of Ohio, have invented a new, original, and ornamental Design for a Desk Calendar or Similar Article, of which the following is a specification, reference being had to the accompanying drawing, forming a part hereof.

Figure 1 is a front elevational view of a desk calendar or similar article showing my new design;

Figure 2 is an end elevational view thereof;

Figure 3 is a top plan view; and

Figure 4 is a vertical cross sectional view taken on line 4—4 of Figure 1.

I claim:

The ornamental design for a desk calendar or similar article, as shown.
